(57) **CLAIM**

The ornamental design for a fitting, as shown and described.

DESCRIPTION

FIG. 1 is a top perspective view of a fitting, showing our new design;

FIG. 2 is a front view thereof;

FIG. 3 is a bottom view thereof;

FIG. 4 is a right-side view thereof;

FIG. 5 is a rear view thereof;

FIG. 6 is a left-side view thereof; and,

FIG. 7 is a top view thereof.

Portions of the fitting are shown in broken lines, which form no part of the claimed design.
